CHAIN STITCH ZIGZAG SEWING MACHINE
FOR ORNAMENTAL SEAMSFritz Ebert, Oberndorf-on-the-Neckar, Germany,
assignor to Mauser-Werke A. G., Oberndorf-on-
the-Neckar, Germany, a joint stock company
of GermanyApplication January 14, 1936, Serial No. 59,144
In Germany January 16, 1935

1 Claim. (Cl. 112—159)

Hitherto known chain stitch zigzag sewing machines are not adapted for high speeds for the reason that roller cams are used for the supplementary drive of the looper and for the control of the needle shank frame. In these known machines the mechanism comprises either two small roller cams or one large roller cam and double transmission, a complicated inner system of gearing being used for the one transmission.

10 Power transmission by roller cams is not suitable for high speeds since very great axial pressures take place therein. The oscillating power transmission levers are greatly stressed, so that under certain circumstances even breakages of 15 the lever may occur. Furthermore, the roller cam drive increases the cost of production of the machines considerably, since either double wheel transmissions or two such cams are necessary.

20 Finally, owing to the roller cams, the clearance space over the table plate between the sewing mechanism and the foot of the casing is considerably restricted, which again causes a reduced output of work.

25 The present invention has for its object a sewing machine which runs perfectly at an extremely high speed yet having none of the defects of the known machine. These advantages are in the main attained by the use instead of a roller cam, of a flat or face cam, that is, a level cam groove arranged in a horizontal plane under the table plate of the machine which is directly driven from the main spindle by a pair of helical wheels.

35 By choosing a face cam as the driving means, it is possible to arrange this, together with the entire drive, underneath the table plate, whereby as compared with hitherto known sewing machines of this nature, the whole space above the 40 table plate between the foot of the casing and the sewing mechanism can be utilized for the passage of the material, which is furthermore entirely protected from being soiled by oil.

45 The guide roller of a double armed lever which is fitted on a vertical spindle, which produces both the supplementary movement of the looper, and also the oscillating movement of the needle shank frame, engages in the cam groove of the face cam. The forward arm of this double armed 50 driving lever produces the supplementary looper movement, whilst the needle shank frame is oscillated by another lever arm fitted on the axis of oscillation thereof. The whole extremely stable driving aggregate thus consists of only the

face cam and the double lever together with its vertical spindle.

In order that the needle may always penetrate correctly, there are provided two possible adjustments for it. Thus, an adjustment of the main position of the needle is possible and an adjustment of the lateral stops. The former is effected by rotating the connecting rod transmitting the driving movement on to the needle shank frame. For this purpose, the connecting rod is provided 10 at its ends with right and left-handed threads, by means of which it is screwed into its end pieces whereby the length of the transmission means, as also thereby the main position of the needle shank frame is altered. The lateral deflection is altered by varying the transmission ratio, the point of application of the connecting rod on to its driving lever being shifted with respect to the axis of oscillation. In this way, various types of stitches may be obtained on the 20 same machine.

In order to prevent entirely an oscillation of the needle shank frame and to be able to produce a straight seam line, the setting device of the driving lever of the connecting rod is so made 25 that its point of attachment can be shifted to the centre of the axis of oscillation of its driving lever. Instead of the zigzag seam, a straight seam is then produced.

Furthermore, various kinds of sewing can be 30 produced without altering the transmission by provision being made that, in addition to the interchangeability of the pairs of helical wheels, the face cam itself can be exchanged.

In order to compensate for small differences in 35 the distance between the spindles when choosing different transmissions, the large helical wheel of the face cam drive is fitted on an eccentric stud which, in known manner, is so rotated that the helical wheels used always come into correct 40 engagement.

Finally, provision is made in order to exchange 45 simultaneously in an advantageous manner all the stitch-forming tongues of the needle plate, such as for example when the number of the tongues is to be changed.

The object of the present invention is more 50 fully explained by way of example on the annexed drawings.

Fig. 1 is a perspective view of the machine according to the invention.

Fig. 2 is a part sectional front elevation of the machine showing some of the essential parts.

Fig. 3 is a vertical section perpendicular to the 55

main spindle of the sewing machine through the axis of the face cam.

Fig. 4 is a plan of the face cam drive.

Fig. 5 is a vertical section of the bearing of an angle lever for the supplementary looper drive.

Figs. 6, 7 and 8 are respectively longitudinal elevation, plan and end view of the needle shank drive.

Fig. 9 shows a number of ornamental stitch work designs which may be produced with the same transmission simply by interchanging the face cam.

Figs. 10, 11 and 12 show the needle plate in plan and side section with two different tongue plates.

The sewing machine or respectively its various members are, as usual, driven by the main spindle 1 running horizontally. The drive of the needle 2 and the main drive of the looper 3 are, as usual, 20 and are not described. The movements of needle 2 and looper 3 are also usual, that is, the needle 2 is oscillated laterally and the looper 3 obtains in addition to its normal movement, a supplementary movement in order to give it a correct movement with respect to the needle 2.

For oscillating the needle shank frame 4 carrying the needle 2, about the vertical axle 5 and for controlling the looper 3 or respectively its supplementary movement, according to the present invention there is provided a face cam 6, that is, a cam groove which with its perpendicular axle 7, that is, with its plane in the horizontal direction, is arranged under the table plate 8. It is driven by the main spindle 1 by means of the helical wheels 9 and 10 and controls a double armed lever 11 which is fitted on a vertical oscillating axle 13 carried on the housing 12 of the sewing machine.

The supplementary movement is transmitted to the looper 3 from the forwardly located arm of the double armed lever 11 by a link piece 15 engaging on a ball pin 14 thereof and an angle or elbow lever 16 which is fitted on a stud 17 rotatably carried in the sewing machine housing 12 (Fig. 5) and by means of a link piece 18 oscillates an elbow lever 21 carried on the arm 19 of the needle drive lever 20. This angle lever drives the looper 3 by means of the connecting rod 22 in the usual way, the necessary supplementary movement being imparted thereto by the face cam 6. The needle shank frame 4 is oscillated by the rocking of the vertical spindle 13. For this purpose, there is fitted at the top of the spindle 13 an arm 23 which, by means of a connecting rod 24 engages a projection 25 extending out towards the rear, which oscillates the needle shank frame 4, (Figs. 2, 3 and 4).

In order to be able to vary the type of stitch, the connecting rod 24 is provided at its ends with right and left-handed threads, so that by rotating it the main position of the needle 2 is varied. Furthermore, the connecting stud 26 of the rod 24 on the arm 23 can be shifted with respect to the axis of rotation 13. For this purpose, there is provided in the arm 23 a radial groove 27 in which the stud 26 may be adjusted and fixed, so that the transmission ratio may be varied.

The face cam 6, the helical wheel 10 fitted on its spindle 1, as also the helical wheel 9 on the main spindle 1, are interchangeable in order to be able to carry out different types of stitching, as can be seen for example in Fig. 9, the different arrangements having all been made with the same pair of wheels but with different face cams.

In order to bring the helical wheels 9 and 10 after their exchange, into correct engagement, the spindle 1 is made as an eccentric stud. By 10 rotating this, the helical wheel 10 is brought into engagement with the helical wheel 9. For this purpose, the eccentric axle 7 in the bearing centre 28 of the face cam housing 29 is arranged to be rotatable and is fixed in the adjusted position 15 by two screws 30.

In order to attain silent running of the machine, the helical wheel 10 is provided with a special toothed rim, of material which works noiselessly, for example, compressed fabric. This 20 toothed rim is fixed on the boss 31 of the helical wheel 10 by screws 32. On this boss 31 there is also fitted the face cam 6 which is fixed thereon by screws 33 and can consequently be easily exchanged in order to be able to use different kinds 25 of cams 6 with the same transmission. By means of a cover disc 34 and screw 35, the inserted face cam 6 is prevented from rising upward.

The face cam 6 or its cam groove controls, as usual, the double armed lever 11 by means of a roller 36 running in the groove 6 which roller is carried on the rear arm of the double armed lever 11 by means of a pin 37. This pin 37 can be adjusted on the arm by which it is axially carried, in any suitable manner in order to be able 35 to adjust the slightly conical roller 36 in the corresponding conical groove of the face cam 6 to allow for wear.

The tongues 38 of the needle plate 39 are interchangeable and the arrangement is so contrived, 40 that tongues 38 of different number can be simultaneously inserted by simple exchange. For this purpose, all the tongues 38 are on a common plate 40 which, by means of a screw 41, is fixed in a recess 42 of the needle plate 39 adapted thereto. 45 The recess 42 is, as shown by Figs. 10 and 11, made wide enough to accommodate the widest plate 40, that is, the one with the most tongues 38. In order to fill up the space of the recess 42 when there are fewer tongues 38 than required for the 50 space intended for the largest number of tongues, there is provided on the tongue plate 40 a projection 43 covering the gap which would otherwise be left.

I claim:

A zigzag chain stitch sewing machine for producing ornamental seams, comprising a needle shank frame, a table frame, a face cam horizontally provided in the machine under the table frame, a double-armed lever having one end thereof cooperating with the face cam, means for driving said face cam, and a second lever for driving a looper mechanism, said face cam oscillating the needle shank frame by means of the double armed lever and the looper mechanism 60 in cooperation with the second lever.

FRITZ EBERT.
